[57] CLAIM

The ornamental design for a two-piece gate bolting assembly, as shown and described.

DESCRIPTION

FIG. 1 is a top, front, and left side perspective view of a two-piece gate bolting assembly showing my new design; FIG. 2 is an explode top, front, and left side perspective view thereof, showing the bolt portions separated when the gate is open;

FIG. 3 is a reduced front elevational view thereof, the rear being a mirror image of that shown;

FIG. 4 is an enlarged left side elevational view of one of the two portions thereof;

FIG. 5 is an enlarged rear elevational view of one of the two portions thereof;

FIG. 6 is an enlarged front elevational view of one of the two portions thereof;

FIG. 7 is an enlarged right side elevational view of one of the two portions thereof;

FIG. 8 is an enlarged bottom plan view of one of the two portions thereof; and,

FIG. 9 is an enlarged top plan view of one of the two portions thereof.

The broken-line disclosure of portions of a gate in the views is for illustrative purposes only and forms no part of the claimed design.

The phantom lines shown in FIGS. 1, 2 and 3 are for illustration purposes only to show the environmental structure of a gate and form no part of the claimed design.
